UNITED STATES PATENT OFFICE.

EDWARD E. CLEMENT, OF WASHINGTON, DISTRICT OF COLUMBIA, ASSIGNOR, BY
MESNE ASSIGNMENTS, TO FREDERICK C. STEVENS, OF ATTICA, NEW YORK.

TELEPHONE-EXCHANGE SYSTEM.

1,107,137.

Specification of Letters Patent. Patented Aug. 11, 1914.

Application filed August 31, 1905. Serial No. 276,634.

To all whom it may concern:

Be it known that I, EDWARD E. CLEMENT, a citizen of the United States, residing at Washington, in the District of Columbia, have invented certain new and useful Improvements in Telephone-Exchange Systems, of which the following is a specification, reference being had therein to the accompanying drawing.

10 My invention relates to telephone systems, and particularly to exchange systems.

It has for its object the improvement of such systems in general, in point of first cost, in point of cost of operation and maintenance, and in point of efficiency.

15 A subsidiary object, though an important one, is the provision of means whereby existing plants may be reorganized without substantial change in present circuits or methods, so as to largely increase their capacity and efficiency.

20 I attain my objects by combining certain features of the so-called manual systems with certain features of the so-called automatic, in a novel manner, the product being 25 what I shall denominate for convenience a "semi-automatic" system.

Keeping in mind the necessity for slight change especially at the subscribers' stations, in changing a plant over with economy, I have designed my circuits so that an ordinary two-wire multiple line circuit may be used, no ground being required at the substation. No special sender is required at 35 the substation, moreover, since the signals are due to makes and breaks of the metallic circuit only, and after the receiver has been taken for use the switchhook may be employed to produce the necessary breaks. To 40 facilitate the manipulation of the circuit, however, I have added a break key, and in practice will provide a simple form of automatic device to produce the same results. At the central office the subscribers' lines 45 terminate in jacks and each has a line signal, as usual in manual installations.

Instead of the operator who answers a call having a pair of plugs, cords, ringing and listening keys, etc., she has a series of 50 single plugs each associated with a supervisory lamp signal and each connected to a trunk line which leads to a first selector switch of the standard automatic type. Heretofore it has been impossible to combine

such automatic circuits with the simpler 55 forms of manual circuits except, at the cost of complicating the manual apparatus beyond the bounds of economy, and losing certainty in the automatic operation; or loading upon the operator the work of sending 60 the impulses to work the automatic switches. The latter has been the expedient universally used in practice, so far as I know now, no true semi-automatic systems after my style of combination having been devised by 65 others. The ordinary automatic systems require a certain number of impulses to be sent over one side of the line, then an impulse or impulses over the other side, then more impulses over the first side of line, 70 and another over the second, and so on. In clearing out, both sides of the line get a ground so that simultaneous impulses are produced. It is manifestly necessary to have a somewhat complicated sending apparatus even in a full automatic system, to produce the proper effects at the proper times, and in practice this is so.

In automatic and semi-automatic systems, as in manual installations, party line service 80 is not only desirable but necessary in order to meet present day conditions and insure proper returns in the face of competition. My present invention not only includes such an arrangement of the best type, but makes 85 it absolutely individual and selective. The party line features, moreover, may be added to any existing automatic installation without great expense and without any change in existing parts and connections.

90 I solve the problems of combination and selection by the use of time-element apparatus. In other words, I introduce as a substitute for varying circuits in the line-call a varying time factor, giving signal impulses different lengths as they are required to operate the working switches or the side switches. In its simplest form this arrangement consists in merely breaking the metallic circuit and immediately closing it 100 again a determinate number of times, depending upon the number desired, then leaving it closed for a longer time than that of any break before making further breaks. The simplicity of the apparatus required for 105 transmitting a signal of this kind is apparent, being as I have stated either a simple break-key or the switch hook itself.

In order to translate the makes and breaks of the metallic line circuit into current impulses on one or the other side of the automatic circuit, I employ in conjunction with my cord circuit a pair of very sluggish relays, controlled by a simple double contact relay connected to that part of the cord which is brought into connection with the line in plugging in to answer a call. When the plug is inserted one of these sluggish relays pulls up, when the first break is produced at the subscriber's station, the other sluggish relay pulls up, and as the breaks rapidly succeed each other both these relays remain up, that is, their armatures do not have time to retract between the successive impulses which they receive from the rapidly vibrating line-controlled relay. At the end of the series of breaks one sluggish relay remains energized, and the other one is given time to retract, owing to the relatively long interval I have mentioned. Thus, I have established different conditions for my sluggish relays corresponding to the time differences in the line transmission, and I cause the armatures of the two sluggish relays to control connections to the two separate sides of the automatic trunk so as to send over one or the other as desired. A third condition is possible when the line circuit remains broken after a conversation, when the calling subscriber has replaced his receiver upon its hook. The relative conditions of the sluggish relays are then reversed, that is, the one which was first pulled up is now retracted, and the other is pulled up. In this condition I cause their armatures to ground or send simultaneous impulses over both sides of the automatic trunk, whereby the usual release magnets are operated.

I solve the problem of partly line selective service by making use of the same principle of different time constants in my relays. I employ a ringing relay so sluggish in its action that the character of the current supplied to it, or of the circuit over which the current is supplied, may be changed during the preliminary operation of the ringing relay so that in finishing its operation it will apply the current so selected, or current over the circuit selected, to the line which is to be called. I cause this ringing relay to pull up on the first impulse of a series whose number is determined by the calling subscriber and corresponds to what I may call the "ringing number", or "ringing letter", of the called subscriber. The breaks in the line or trunk are caused to select the particular current required, and after once pulling up I proportion the parts of the ringing relay so that it will not again fall back until the last break has been sent and the line remains closed for a definite time. Then, in falling back, and between the

position of attraction and that of complete retraction, I cause the ringing relay to connect the generator to line. In other words, the relay acts as a ringing key, and the accompanying selector acts like the selective keys in an ordinary manual set. When the ringing relay armature is down all the way the selective device is restored, the stepper disk or arm being put back to zero or normal position.

In the system hereinafter described as embodying my invention I have incorporated what I now consider the best and most advantageous features from a commercial standpoint. The selection of the ringer desired is by means of a specific frequency of ringing current, according to the so-called "harmonic" idea. I do not limit myself to this, however, for I can also use, as well, what is known as the "Leich" system, or the Sabin system employing ground taps at the subscribers' stations and pulsatory currents of opposite signs. In fact, I may designate this part of the present invention an automatic selective ringing key and connections for automatic systems. Each subscriber has a number or letter assigned to him constituting his "ringing number" or "ringing letter". Thus, all number 1 parties on polystation lines have the ringing number 1, all the next parties the number 2, and so on; or for letters the party line subscribers may be divided into classes "A", "K", "F", "Y", or the like. In sending a number a calling subscriber proceeds exactly as in a manual system, *i. e.*, sends the line number, then the ringing number. Thus, for example, the third party on line 2224 is "3", and his number appears in the directory as follows: 2224-3. In sending this number, the calling subscriber, if using a key or single number sender such as commonly employed in Strowger systems, sends 2, 2, 2, 4, and then 3. The first four numbers select the line wanted. The first impulse of the fifth number lifts the ringing relay or solenoid, which has then been brought into circuit at the connector switch, and the next two impulses shift the ringing selector two steps, cutting off successively the normal or low current, and the next higher, leaving number 3 current on the key. Then the line remains undisturbed, as the calling subscriber simply waits, so the solenoid lets go its core, which in retracting connects the selected current to line, and then after its descent—which may be made anything desired in point of time, and which of course determines the duration of the ring—cuts off the current, recomplete the line and restores the ringing selector to normal, ready for a new operation. If the called subscriber does not immediately answer and a repetition of the ring is required, the caller simply sends the ringing number "3", "3", "3".

"3", as often as required. This will do nothing after the complete operation of selection but repeat the ring.

An ancillary advantage in my system is the absence of a push button or other calling means, so that for party line work I actually decrease the subscriber's apparatus instead of increasing it.

Other advantages of the invention will appear from the following description and the accompanying drawings illustrating the same, wherein the system is shown to which I have referred.

In the drawings, Figure 1 is a face view of a panel carrying a pair of solenoids or sluggish relays, used in the cord circuit for translating line impulses into trunk impulses. Fig. 2 is a vertical section of the relay D in Fig. 1, taken on the line α — α . Fig. 3 is a diagram showing a party line with four subscribers' stations thereon, an operator's connecting cord circuit with a pair of sluggish relays, and connections to a first selector switch. Fig. 4 is a diagram complementary to that of Fig. 3, showing the circuits of the first selector switch and a trunk with a second selector switch, a trunk therefrom to a connector switch, selective ringing apparatus for the connector, and a connection from the connector bank contacts to the subscriber's line of Fig. 3, to illustrate the scheme for ringing back on the calling line without getting a busy test. Figs. 5 and 6 are diagrams similar to those in Figs. 3 and 4, but showing only one party on each line, and an ordinary ringing relay in a connector circuit. Fig. 7 shows a modification of the circuit of Fig. 6, and Fig. 8 is a detail.

Before proceeding to detailed description of the circuits, I will first briefly describe the pieces of apparatus employed. These comprise the sluggish relays, D and D', the automatic switches with their operating parts and magnets, the ringing relay D² and its selector D³, D⁴, and the subsidiary parts employed at the subscriber's station. I will then take up Figs. 5 and 6, from which the party line apparatus is omitted, finally passing to Figs. 3 and 4, which show the full system with party line arrangement.

The sluggish translating relays to which I have heretofore referred as distributing agents for the line impulses, are best shown in Figs. 1 and 2. Each consists of a solenoid with a long movable core, and each pair is mounted for convenience on a panel d^x . The mechanical structure of each solenoid in a pair is the same, but their circuit springs are different in number and arrangement. The solenoid D closes its springs together momentarily once in pulling up and once in letting go. The solenoid D', on the other hand, opens its springs on pulling up and closes them together when its armature is

fully retracted. Turning to the solenoid D, as shown in Figs. 1 and 2, it consists of a spool formed of a tube d^{16} with heads d^{17} , the upper end of the tube fitted with an iron plug d^{14} having a central threaded opening 70 to receive the valve nut d^{11} , which serves to secure the spool to a bracket d^{10} mounted on the base panel. The valve nut has a central opening to receive the stem d^{13} of a check valve d^{12} , which rests upon the upper face 75 of the nut d^{11} , and is faced with rubber, leather, or other relatively soft material. The opening d^{15} in the valve nut is large enough to afford a clearance space around the stem d^{13} , and the panel d^x is mounted vertically, so that the axes of the solenoid and the valves will also be vertical. Fitted snugly to the tube d^{16} is the iron core d , which normally rests in the position shown, partly withdrawn from the coil, leaving an 80 air space above it. The lower end of the core is fitted with a projecting screw d^{30} , carrying an insulating disk d^2 adjustable by means of upper and lower nuts. Beneath the end of the screw an adjustable stop screw 85 d^{31} is mounted in a post d^{32} carried on the panel. This stop screw is fitted with a lock nut so that it can be set accurately and then locked. There is no retracting spring shown for the core d , the force of gravity being depended upon, and it being possible to load the core to any desired extent.

The relay D' is similar in every respect to the relay D, except, as I have stated, in the matter of its springs. Both the brackets d^{40} 100 have depending arms d^{48} , upon which the respective contact springs are mounted. There are three of these springs, d^4 , d^5 , and d^8 , for the relay D, all normally separated but momentarily closed together when the core d goes up or down, the edge of the disk d^2 in such case riding over the end of the spring d^4 . For the relay D' there are four springs, d^6 , d^7 , d^9 , and d^{11} , the first two of which tend to close together, and the others to open when the core of the solenoid is up. When the core is down, the insulating disk d^2 rests against the spring d^5 , breaks its contact with d^7 , and forces together the three springs d^6 , d^9 , d^{11} . The screw d^{31} of the relay D' is set and locked in its post so that the disk d^2 will remain in contact with the spring d^5 when the relay is inactive.

The tube of each solenoid is preferably brass or copper, and instead of accurately fitting the cores I may employ any desired form of packing to prevent a free escape of air. The operation is as follows: When either solenoid receives current the core is at once sucked up into the tube, and this very 120 rapidly, as the check valve d^{12} rises from its seat and permits the air to escape freely from around its stem. A short break of the solenoid circuit will not suffice to let the core fall far enough to reach the spring in either 125 130

case, however, for on the downward movement the check valve d^{42} closes upon its seat and the air enters very slowly. During a succession of impulses therefore, if rapidly transmitted, the core d or d' will simply vibrate slightly without descending, and only on a long break will it fall far enough to reach its springs.

The ringing relay D^2 shown in Fig. 4 is of the same type as the relay D and D' , consisting of a solenoid with a long core d^o carrying a terminal insulating disk, which when down rests on springs d^{15} and d^{20} , and when up pulls up springs d^{12} and d^{17} . During its ascent and descent, and while it is between its extreme positions, it leaves the springs closed in pairs as follows: $d^{12}-d^{13}$, $d^{17}-d^{18}$, $d^{14}-d^{16}$, $d^{19}-d^{20}$, and $d^{21}-d^{22}$. When all the way down, the last named pairs are opened, and $d^{15}-d^{16}$ and $d^{20}-d^{23}$ are closed. The springs $d^{21}-d^{22}$ are simultaneously opened, in order to cut off battery current from wire 134 of the detent magnet D^4 , to deenergize the latter and permit the restoration to zero position by its spring of the ringing selector switch.

Associated with the ringing solenoid is the switch to which I have referred as the "selector" or "ringing selector." This consists of a pair of switch arms 144 and 145 on a common spindle carrying a fixed ratchet wheel with which meshes a pawl on the end of the lever of the armature of magnet D^3 . This lever is marked d^{30} , and the pawl is pivoted to its end so that in passing up it will yield and move over the teeth of the ratchet but in moving down it will turn the wheel. When in disuse it remains out of engagement with the wheel. The ratchet wheel has a detent or stop pawl carried on the armature lever of the magnet D^4 . When the magnets D^3 and D^4 are deenergized, both the working and the stop pawls are held out of engagement with the ratchet, by gravity or suitable springs. When the magnet D^4 is deenergized both pawls are off and the ratchet wheel returns to zero or normal position under the influence of a suitable coiled spring. The circuit of magnet D^4 is controlled, as already stated, by the normally open springs d^{21} , d^{22} of the ringing solenoid, D^2 . Cooperating with the arms 144 and 145 are fixed contacts, which may be springs or studs, connected to the generator circuits. As a pair of arms starts to move around step by step, directed by the ratchet and driven by the magnet D^3 , it connects first the generator G^3 , then G^2 , then G' , then and finally G , to the wires 135 and 135^a leading to the ringing solenoid.

The next apparatus to be touched upon is the typical automatic switch employed. It is to be understood that I do not lay claim herein to a particular form of switch, nor am I limited to any particular type, but the

circuits and other apparatus have been designed in the form illustrated for convenient operation with what I may designate as the Strowger type of switch. This switch was originally disclosed in Patent Number 70 447,918, granted March 10, 1891 to Almon B. Strowger; and has since been improved as shown in Patents Number 672,942, granted April 30, 1901, and Numbers 815,176 and 815,321, granted March 13, 1906, to Keith 75 and Erickson.

In order not to depart from well-known forms of the circuits, and to gain in simplicity of description, I have chosen herein to adhere to the type mentioned, as the original two-motion switch. Another point in this connection is that since the Strowger improved switch is in wide commercial use my present circuits will be more readily perceived to be applicable to existing installations in the form thus chosen than if I set forth more unfamiliar forms. 80 85

The distinguishing feature of the switch is its two direction movement. The line contacts are arranged in curved rows embedded 90 or supported in insulating arcs or segments, and the switch wipers or movable contacts are supported and moved by a vertical spindle which may be stepped up by one magnet, called from this motion the "vertical magnet," and which may be turned around its axis by another magnet called from the fact the "rotary magnet." Originally these two magnets were controlled by two corresponding relays one connected to 100 each side of line, and working so that when impulses were sent over one side of the line the vertical relay and its vertical magnet were operated, and when over the other side of the line the rotary relay and magnet were 105 operated. From this method of operation it became customary to call the two corresponding sides of the line the "vertical side" and the "rotary side" respectively. At the present time and according to the 110 standard practice in the commercial automatic systems, the vertical relay alone does the stepping, operating the vertical and rotary magnets (which still retain their same functions as originally) in succession, and 115 being shifted from one to the other for that purpose by a so-called "side-switch," which is controlled by what was, and is still called, the rotary relay. This arrangement was adopted because other things than the mere 120 stepping of the spindle and contact wipers must be provided for and the side-switch is a convenient apparatus for the purpose.

The switch then consists of a frame having top and bottom bearings, as shown in 125 the Keith and Erickson patent referred to, with a vertical spindle therein carrying contact wipers connected to a flexible cord attached to terminals on the switch frame and thence to the trunk leading to the switch. 130

Rows of multiple contacts connected to other trunks leading to switches of a lower order or to subscribers' lines are arranged in curved lines around the spindle and concentric therewith. The side switch consists of a set of switch arms having a common pivot so they will all move together, these being shown herein at s^{42} , s^{43} , s^{44} , and s^{41} , of Fig. 3, and elsewhere. The arms are all put back into a normal or zero position, (in which they are illustrated herein), when the switch is at normal or out of use. After the switch has started they are held only by a step by step escapement controlled by a so-called "private magnet," S^4 , or S^{15} , Figs. 3 and 4, and this magnet by its attraction and release of its armature permits the switch to take step by step the successive positions indicated by the contacts 41, 42, 43, 38, 39, 40, 44, 45, 46, and 49, 47, 48. The magnet thus designated as a "private" magnet is really a test magnet, operating to select a trunk or line contact that is free and not in use. If the very first contact on which the wipers of the main spindle come happens to be free the side switch might not be moved, unless special provision is made, because the private magnet must, as stated, make two steps to work the escapement. For this purpose the rotary magnet, (shown at S^6 and S^{11} in Figs. 3 and 4), which is a vibrator making and breaking its own circuit as well as turning the spindle of the switch, has its armature so adjusted that it will knock against and hold up the armature of the private magnet in its back stroke of closure. Thus when the rotary magnet starts it takes one stroke, the wipers move around one step from zero to the first contact pair, and then as the rotary magnet armature retracts preparatory to another movement forward the private magnet is left in control of the situation. If the trunk connected to the contacts on which the wipers rest is busy a ground will be on them and the private magnet will therefore maintain its armature up, as the rotary magnet left it, and another stroke of the latter magnet will move the wipers to the next contact. Here the operation is repeated, and so on until a pair of contacts are found which are not busy, when the private armature will fall back as soon as the rotary magnet retracts, and the side switch will promptly shift a step. This private magnet in the first and subsequent selector (as distinguished from connector) switches opens the vertical magnet circuit when it is energized, so that only the rotary movement of the spindle and wipers can take place at that time.

In order to give the two motions of the spindle and wipers, the former is provided with a circular ratchet and a long pinion joined together, the pinion toothed vertically

gage it at any elevation to which the vertical magnet may raise it. This is well shown in the patents I have mentioned and needs no detailed description.

There are usually provided several switches of each digit, that is duplicates to which the lines or trunks of the next order of switches are multipled. The reason for this is obvious. In the selector switches the vertical movement selects a row containing the desired thousands or hundreds as the case may be, and the rotary motion of the spindle then moves it around the row until an idle pair in that row, or for that digit, is reached. The multiples of a trunk or line are usually represented as shown in the drawings here-with, as small parallel lines w^4 , w^5 , w^7 , w^8 , etc. joined to the line ends. These are supposed to be distributed in the different switch banks of the same number or digit. The spindle and its wipers are usually shown as in Figs. 3, 4, 5, and 6, the former being lettered w and the latter respectively w' , w^2 , and w^3 for the selectors. It will be understood after the foregoing explanation that the spindle w or w' is moved up step by step through a vertical ratchet operated by the magnet S^5 , S^{12} , or S^{20} ; and it is turned around its axis by the rotary magnet S^6 , S^{11} or S^{21} , as the case may be. In the connector switches there is this difference over the selectors, that the rotary magnet is not a vibrator self actuated, but is moved step by step just like the vertical magnet. This is because no idle trunk selecting is to be done in the connector, but a tens row and a definite unit in that row are to be picked out instead.

Having thus set forth the principal mechanical features of the switches, the circuit descriptions will be readily comprehended. It remains to refer briefly to the subsidiary apparatus at the subscriber's station. In Figs. 3 and 5 I have shown the usual transmitter, receiver, switchhook, ringer and condenser. These may be of any usual and approved type. They are sufficient to produce all the desired effects in my present system without any other apparatus, especially in skilled hands; but as telephone subscribers and users are too often unskilled, I find it convenient, not to say necessary, to provide some special pieces. These are the signal Q^o and the key or sender K . The signal is a polarized magnet with a card or target fastened to the extreme end of its clapper rod, exactly as the clapper of a ringer is secured, so as to get a long path of travel for the target. In the face of the telephone casing, as shown in Fig. 3 particularly, I form a window, and the card of target q lies behind this window. The magnet Q^o is either bridged across the line and wound to a high resistance and impedance, or it is as shown included in the talking circuit

branch 5 with the transmitter and receiver, in which case it is low wound so as to offer as little impedance as possible to the voice currents. It is polarized and adjusted so that the current normally on the line, that is when a plug is not in the answering jack, is of a direction not to operatively raise its target. When a plug is inserted, however, this target is raised at once owing to a reversal of current. This is accomplished very simply, as will appear in the circuit description. The target preferably bears upon its face the word: "Number?" so that when it appears the word indicates that the sending apparatus is to be manipulated to select the line wanted. This is literally the machine asking for the information usually given an operator and which is of course fed to a machine mechanically. Any other suitable word can of course be used, such as "Send" or "Select" or the like, but I consider the first the best.

No specific description of the key is necessary, but it will be observed that as only momentary breaks of the circuit are required it is quite possible to omit the key and use the switchhook H, since the motion in either case is precisely the same.

I will now take up the circuits, and as a preliminary I may state briefly the operation. In calling, the subscriber takes down his receiver and waits until he gets a signal to go ahead. The operator gets the usual calling signal by means of a lamp or shutter, and inserts an answering plug. The insertion of this plug energizes the cut-off relay, which disconnects the line from the signal relay and its battery, and connects the line to main battery through the cord. The connections of the battery and the cord are the reverse of those on the line before a plug is inserted, hence the insertion of the plug, by sending reversed current to line operatively energizes the subscriber's signal, displaying an indication for him to proceed. Thereupon he manipulates his key or switchhook, or other make and break device as in an ordinary automatic system, sending the groups of impulses which make up the digits of the number wanted. Since the answering plug has connected with it responsive relays corresponding to the supervisory relays of the ordinary manual system, and since the cord circuit is connected (through the condensers for conversation) with a trunk leading to an automatic switch, I cause the impulses to act upon one or more of the relays to repeat over the trunk to the switch or switches and thus make connection with the wanted line. If that line is a party line, the calling subscriber transmits a fifth or extra group of impulses after he has selected the line, this group of impulses being effective to select and put upon the called line suitable current to ring the bell

at the particular station wanted. In case the calling subscriber is on a party line and desires to call one of the other parties on his own line, means are provided whereby he may select his own line, although it is calling, without having it test "busy", although if he should call another line which was in use it would test "busy" and he would find it impossible to connect therewith. After completing the connection, the calling subscriber retains control thereof until he finally hangs up his receiver, although what are known as back release magnets may be placed in each connector switch so that the line of the called subscriber cannot be "tied up". Upon the calling subscriber replacing his receiver, his metallic circuit is broken and remains broken, which causes a reversal of the solenoid conditions in the cord circuit, to send proper impulses over both sides of the metallic trunk circuit, to release the automatic switches; and at the same time the cord relay, which works the solenoid, lights the supervisory lamp, informing the operator that disconnection is desired. It is to be noted that a subscriber may hang up long enough to restore the switches, which requires perhaps two seconds in the system I have operated, and may then take his receiver for a new call without further delay. If the operator has pulled the plug his signal to go ahead does not show until he is given another plug and set of switches, but if she has not pulled the plug his signal will show at once, and he can make his call without delay.

Referring now to Figs. 5 and 6, which show a system without party lines, and regarding the two figures as one continuous diagram for the purposes of this description, A is a subscriber's station provided with the usual transmitter T, receiver R, ringer Q, condenser C, switch hook H, and connections. In addition to these I provide the polarized magnet controlling the signal target, lettered respectively Q^o and q' , and the signaling key K. Both the key and the signal are in the transmitter branch, and are normally out of use. They may be placed in a shunt of the transmitter branch, especially the signal, which should then be high wound. In the present illustration, being in series with the talking apparatus, it is supposed to be very low wound, or of very low impedance. The line wires 1 and 2 are normally closed at the sub-station through the ringer, condenser, switch hook, and key, by way of the wires 3 and 4. When the hook is up the path is shifted to 1-3-H-R-T-5-Q^o-2. At the central station the line wires terminate respectively, at the contacts n and n' of the cut-off relay N, which are normally in contact with terminals of the wires 7 and 8, leading, respectively, to the line

relay M and battery by way of wire 1000, and to ground. When the cut off relay N is excited the terminals n , n' are connected to wires 9 and 10 leading to the connection terminals which are in multiple and comprise the answering jack J and the multiple switch terminals w^7 w^8 which are supposed to be distributed in different connector switches through which this line can be reached. The relay N is in a ground tap from the sleeve side 10 of the terminals. The relay M through its armature m controls the circuit of the line signal lamp m' .

For answering calls the operator is provided with a plug P whose tip and sleeve are connected respectively with the cord conductors 11 and 12, and thence through the condensers C' and C² to the trunk wires 13 and 14 leading to the automatic first selector switch W. Across the plug end of the cord are bridged the relays S S², which correspond very closely in their arrangement and function to the supervisory relays of an ordinary cord circuit. The main battery B is included in the bridge between them, the path from one side of the cord to the other being as follows: B, 21, S², 18, and from the other side 11 by wire 17, S, and ground to battery. The relay S² being on the live side of battery, takes current as soon as the plug is inserted by the following path: B, 21, S², 18, 12, P, J, 10, N, ground, to battery. This energizes both relays S² and N, the armature s^2 is attracted, and the battery is connected to the armature s of the relay S. This relay S takes current returning from the subscriber's station, and hence is energized only so long as the subscriber keeps the circuit closed. This control by the subscriber enables me to use the relay S for my controlling relay, which it really is. Like the supervisory relay in a manual system, it follows every motion out of the subscriber's hook or key. It has front and back contacts, the former connected by wire 23 to the solenoid D', through branch wire 33, and to ground at 31. A branch 29 is taken through the springs d⁴ d⁸ of the solenoid D, and thence to the trunk wire 14 by branch 34, having also a branch 35 connected to the spring d¹¹ of the solenoid D'. From the back contact of the relay S the wire 25 goes to the supervisory or clearing out lamp s⁰, also through a branch 26 to the solenoid D and ground at 31, with a second branch 30 to the spring d⁷ of the solenoid D'. The battery supply for certain portions of the solenoid operation is thus controlled by the relay S, but for certain other portions it is independent of the relay, the wire 22 being connected direct through the branch 220 to the spring d⁹ of the solenoid D'. From the spring d⁹ of this solenoid a wire 36 goes to the trunk

conductor 13, which corresponds to the ordinary vertical side of line in a full automatic system. It is through the two wires 34 and 36 that the proper pulsations of current are sent to the vertical and rotary sides, 13 and 14. 70

Commencing with the wires 13 and 14, the rest of the diagram relates to purely automatic apparatus. I have shown a first selector switch W, whose trunk line is 13-14, and is permanently connected to, and associated with, the answering plug P. It is to be observed that the first selectors are usually the same in number as the subscriber's lines, and that what I have done therefore by putting these first selectors on plugs is to reduce the number of first selectors to that of the plugs, or from 100 per cent. to not more than 15 per cent., a saving of 85 per cent. minimum. Moreover, the manual equipment is that now employed in many large installations, and this system enables me to increase their capacity enormously without other change than that of connecting multiple jacks to 80 act as answering jacks, and adding a number of automatic switches ranging from 15 to 35 per cent. of the number of lines, according to the size of the plant, and the amount of business it carries. The number 90 of operators is greatly reduced, since one operator can handle at least five times the number of lines in this way that she can handle in a straight multiple system. For clearness I should add that in a full automatic system the number of switches ranges from 120 to 135 per cent. of the number of lines. Taking the maximum therefore, I save 75 per cent. as against an automatic system, the answering jacks being a small 95 off-set, and the number of operators employed costing much less than the mechanics necessary to care for the automatic switches. 100

I have already described the switch which I have shown as a type, and I need only say therefore, that w is the spindle carrying the wipers w', w², w³, which are supposed to sweep around over horizontal curved rows of contacts to which they are vertically stepped up, these being typified by w⁴, w⁵, 110 w⁶. The magnet which directly steps up the spindle is S⁵, and the magnet which rotates it after it is stepped up to the desired row of contacts is S⁶. The so-called private magnet is S⁴, whose armature s⁴ controls the circuit 115 52 of the vertical stepper magnet S⁵, and by means of a mechanical connection not shown works the escapement for the side switch whose arms s⁴¹, s⁴², s⁴³, and s⁴⁴ are all rigidly attached together and move 120 as a unit one step, i. e. over one contact each, at a time. The side switch is shown in the normal position it occupies when the selector is at rest, and to this position it is brought by a mechanical connection with 130

the spindle when it falls to its normal position of disuse. The spindle is prevented from falling after being rotated on any row by a stop or detent pawl and also by the engagement of the wipers with the horizontal row of contacts, and it is held against turning back until released by a second arm on the same detent. This detent pawl is controlled by the release magnet S^7 , whose circuit is also controlled in part by the private relay S^4 , and is finally controlled through the wiper w^3 , as will appear in the statement of operation. The relay S' is the vertical relay, which first controls the vertical stepper magnet S^6 then the rotary magnet S^8 , and is finally disconnected in the first and second selectors.

S^3 is the rotary relay, which, in the first two positions of the side-switch, responds to single impulses over the trunk wire 14 to close the circuit of the private magnet S^4 , in order to move the side switch.

The connection between the rotary magnet S^6 and the private magnet S^4 is as follows: when the rotary magnet starts to vibrate in the second stage in the operation of the selector, a projection carried on its armature kicks against the armature s^4 so as to hold the latter up on the stroke and release it for test afterward. In case the first contact the wiper w^3 comes on is idle this would be necessary because as previously stated it takes an up and back stroke of the armature s^4 to release the escapement each step. Hence if no ground were encountered and no mechanical means were provided, there would be no second forward movement of the armature s^4 . Since each full vibration of the armature of the rotary magnet S^6 moves the spindle and wiper w^3 the space of one contact, however, and since the kick of the rotary armature simultaneously moves up the armature s^4 at the same time, then if the wiper w^3 finds no ground on a contact the armature s^4 is in a position to release the escapement at once and so stop further rotation by letting go the side switch and cutting off the rotary magnet at contact 42, the switch arm s^{41} then passing off that contact to the last one 43, a blank. If, on the other hand, the wiper finds ground, it will hold up after the kick up, and keep the side switch set on contact 42 until another step has been taken, and so on.

The parts and connections in the second selector are all the same as in the first selector, except that the vertical and the rotary relays S^9 and S^0 by their joint action pulling up both their armatures at the same time close the two contacts 103 and 107 together and so close the release circuit as follows: 70, 103, 107, S^{13} , 75, 1000, battery, from the private bank contacts w^6 and so back to the wiper w^3 , wire 61, relay S^8 , 60, s^{44} , 48, 59, and ground. This releases the

first selector as well as the second one. To do it requires the simultaneous operation of both relays S^9 and S^0 by impulses over both wires 67 and 68. The vertical magnet of the second selector is marked S^{12} , the rotary magnet S^{11} , the release magnet S^{13} , the private magnet S^{15} , the test relay S^{14} . The side switch has arms s^{45} , s^{46} , s^{47} , and s^{48} , all working simultaneously, as before. The second selector as a whole is marked W' .

The multiple bank contacts w^4 , w^5 and w^6 of the second selector are connected to trunk wires 97, 98 and 99 of the connector switch W^2 . This last is different in several respects from the selectors. In the first place, the vertical relay S^{16} is not deprived of its control after the first set of impulses and the first step of the side switch arms, being in fact independent, as is also the rotary relay, of the side switch, their bridge wires 100 and 102 being permanently connected to the trunk wires 97 and 98. In the second

place the rotary magnet S^{21} has a stepper pawl which turns the spindle w^4 only step by step one step at a time, the magnet not being a vibrator like the others, S^6 and S^{11} .

It should be here stated that these magnets are shown each with a wedge shaped insulating extension which as the armature is attracted passes between and breaks apart the terminals shown between the windings.

This is the usual diagrammatic way of representing these rotary magnets, but any other form of vibrating contact might be employed, such as the ordinary buzzer contacts closing on the back stroke. The magnet S^{21} has no such contacts and responds only to pulses from the controlling relay S^{16} .

In the third place, instead of the side switch arm 146 coming to a blank on its third step, it connects the local wire 120 of the vertical relay S^{16} to the wire 127 of the ringing relay D^2 , which thereafter remains under the control of the said vertical relay.

Finally, there is no separate wiper for testing, on the spindle w^4 , the test being made directly on the talking wiper w^5 , as will hereafter appear. The release magnet or relay is S^{22} , controlled as in the second selector by the joint action of the vertical and rotary relays S^{16} and S^{17} . The wipers w^5 and w^6 of the connector switch W^2 co-operate with line terminals directly, w^7 , w^8 , heretofore noticed in connection with line 1-2.

I have shown another line 1-2 at 105 the right of Fig. 6 which is supposed to be equipped at central and the substation just as the line in Fig. 5, already described.

Having thus presented, briefly but with an attempt at clearness, the arrangement of the switches, which as stated in themselves form no part of the present invention, I will now proceed with the statement of operation, in which the details of the entire system will be brought out fully.

Having thus presented, briefly but with an attempt at clearness, the arrangement of the switches, which as stated in themselves form no part of the present invention, I will now proceed with the statement of operation, in which the details of the entire system will be brought out fully.

We will assume that the subscriber A desires connection with say the subscriber on the line to the right of Fig. 6, who may for convenience be called A'. A takes down his receiver R and waits just as he would in a manual system. As soon as his hook H rises the following circuit is closed for the line relay M: B, 1000, M, 7, n, 1, K, 3, H, R, T, 5, Q°, 2, n', 8, ground to B. The relay M becoming energized pulls up its armature m and lights the lamp m' . The operator perceiving this signal inserts the plug P in the answering jack J, closing a circuit through the cut-off relay N as follows: B, 15 1000, 21, S², 18, 12, P, J, 10, N, ground to B. Relay N becoming energized pulls up armatures n and n' and cuts off the relay M and ground 8, closing the line wires 1 and 2 and so the line to the cord, as follows: B, 1000, 20 21, S², 12, P, J, 10, n', 2, Q°, 5, T, R, H, 3, K, 1, n, 9, J, P, (tip), 11, 17, S, ground to B. This energizes relays S², and S, the relay N having already taken current however over the circuit traced. The first effect of this is 25 to cause magnet Q° at the substation to turn over its armature, raising the target q' so that it will show through the little window in the front of the telephone casing, the magnet being so polarized and connected 30 that the current through line relay M was of the wrong direction and would not raise the target, but now receiving reversed current from battery through the sleeve side of line. The second effect to be noticed is 35 that relay S² put current on the wire 22 and hence on the armature of relay S, but the latter being now attracted the lamp wire 25 is cut off and the lamp remains dark. The branch wire 26 is also cut off, but the 40 wire 23 takes current through the front contact of the relay S and the solenoid D' immediately pulls up its core, closing together the springs d^5 and d^7 and opening the springs d^5 , d^9 , and d^{11} . The former 45 pair complete the wire connection 36, 30, 26 to the back contact of relay S, so that if that relay were now deenergized without deenergizing the solenoid D', a pulse of current would be sent to wire 13. However, the 50 parts remain unmoved until the subscriber does something at this point. It will be observed that the solenoid D is deenergized and its springs d^4 , d^8 are open. The subscriber getting the signal q' set before him, 55 preferably bearing the word "Number?", now sends a group of short breaks by means of the key, corresponding to the first digit of the number wanted. Suppose that number to be 2223. He sends two short breaks 60 by means of two taps on the key. The effect of this is to cause the relay S to let go its armature twice in quick succession and pull it up again each time, the second time holding it up. On the first retraction the solenoid D' of course loses current, and so on

the second, but neither break is long enough to permit the core d' to drop far enough to reach the springs, and each make pulls it up again to the top. On the other hand the solenoid D takes current on the first break, 70 since its circuit is then closed as follows: B, 1000, s^2 , 22, s , 26, D, 31. This solenoid pulls up its core d at once and fully, although the pulse of current it receives is short, because it is so constructed that the up stroke 75 is very quick. On the line make following the break the core d of course starts to descend, but there is not time before the other pulse comes due to the second break in the line, and so the springs d^4 , d^8 remain open. 80 It should be noted that nothing is done by the momentary closure of the springs on the up stroke, as their source of current supply is cut off, the armature s being back at that instant. Each time the break comes in the 85 line, however, a pulse is sent to the wire 13, (the vertical side of the automatic circuit) by the following path: B, 1000, 21, s^2 , 22, s , 26, 30, d^4 , d^8 , 36. The first of these passes along the wire 13 to the switch W and 90 through its vertical relay S' by the following path: 13, s^{43} , 38, 19, S', and ground to B. The relay S' becomes energized and pulls up its armature, closing the following circuit: B, 1000, 55, 54, S⁵, 52, 65, 64, 51, 50, ground 95 to B. This energizes the magnet S⁶, which immediately acts to step up the spindle w one step. The second pulse follows the same route, by the same transmutations from substation break to automatic pulsation, and the 100 magnet steps the spindle up another step, so that the wipers w' , w^2 are opposite the second row of contacts in the banks, these being connected to trunks leading to a set of second selector switches numbered two thousand. 105 Some of these may be busy, and it is now the function of the switch W itself without any act on the part of the subscriber to get on an idle trunk and an idle second selector. For this purpose the side switch must be worked, 110 and this is done by a pulse of current over the rotary trunk wire 14 as follows: When the subscriber let go the key the second time the circuit remained closed at his station and the armature s consequently remained up. 115 The solenoid D was therefore deprived of current, and as its core sinks down it passes the springs d^4 , d^8 , pressing them together and closing the following circuit, which is now possible because the armature s is up: 120 B, 1000, 21, s^2 , 22, s , 23, 29, d^4 , d^8 , 34, 14, s^{43} , 20, S³, ground to B. This energizes the relay S³, which closes the circuit of the private magnet as follows: B, 1000, 55, S⁴, 500, 50, ground to B. The magnet S⁴ pulls up 125 its armature s^4 , cuts off the vertical magnet S⁵ at 65 by opening the pair of springs 64-65, and as the impulse ceases to energize it, permits its armature to retract and move the escapement the second half of its step 130

releasing the arms s^{41} , s^{42} , s^{43} , s^{44} , so that they all move one step, coming respectively on the contacts 42, 39, 45, 47. The circuit of the rotary magnet S^6 is then closed as follows: B, 1000, 55, 54, S^6 , 53, 42, s^{41} , ground to B. The vibrator magnet S^6 then commences to move its armature back and forth and with it the projection which kicks the armature s^4 of the private or escapement magnet, and the pawl which steps around the spindle w . At the first step the spindle is moved so that the wipers come onto the first pair of contacts, the armature s^4 is kicked up to put the escapement in operative condition, and the wiper w^3 if its contact is busy and grounded because another connection already exists thereon, closes a circuit for the test magnet as follows: ground, B, 1000, 55, S^4 , 470, 47, s^{44} , 60, S^8 , 61, wiper w^3 and so to the ground on said wiper, to battery B. The two magnets S^4 and S^8 it will be observed are in series in this circuit. The former will be effectively energized by current therein but not the latter, owing to divergent resistances. Hence the armature s^4 will hold up on the second half of the step after the armature of the rotary or vibrator relay S^6 has retracted, and the second movement will be permitted. As the wipers come on the second contacts the operation is repeated. The armature of S^6 kicks up the armature s^4 , the wiper w^3 tests, but suppose in this case there is no other connection on that trunk thus tested, and so there is no ground on the contacts w^6 . The circuit last above traced does not exist, the magnet S^4 gets no current as the armature of S^6 retracts and since the kicker is withdrawn there is nothing to hold up the armature s^4 so it too retracts and lets go the escapement, which at once steps around the arms s^{41} , s^{42} , s^{43} , and s^{44} the last step. The first named cuts off the rotary relay S^6 , and that instantly stops the rotation of the spindle w , which thereafter stands with its wipers on the contacts thus selected. The second named disconnects the trunk wire 13 from wire 19 and connects it to the wiper w' through the wire 15. The third named does a similar change, connecting wire 14 on 16 and wiper w^2 . The last named connects the test magnet S^8 to the ground through contact 48, thus also connecting a ground to the contact w^6 (see Fig. 6, left hand side), so that as long as the connection we are tracing exists that trunk will test busy and be free from use by others. This leaves the line 1—2 connected through wires 13—15—67, and 14—16—68 to the second selector W' . The statement of the operation has taken some pages and considerable time, but of course in practice the subscriber has been waiting only a couple of seconds to send the second set of impulses. I have found in practice that the time required, averaged in

a good many trials, for the rotary magnet to select an idle trunk, where most of the trials went beyond the fifth contact, was less than a second, and it is stated by the manufacturer of the type of switches I show that the whole ten contacts can be tested in one-half a second. The movement of the spindle in rotating is continuous, there being no separate steps as I have described them. Keeping this time in mind, it is apparent that the subscriber, if he leaves an interval at all, will leave a long enough one in the very nature of things to permit selection of an idle second selector. He then sends two more short breaks by two taps on the key K. The results in the second selector circuit are absolutely the same as in that of the first selector, except that it is now the desired hundred that is picked out in stepping two rows, and an idle connector switch W^2 that is picked out in the row. The apparatus of the second selector is also the same as that of the first selector except that the relays S^9 and S^0 have restoring or releasing contacts, which the relays S' and S^3 lacked. These contacts are marked 103 and 107. When the vertical relay S^9 or the rotary relay S^0 is operated alone no effect is produced on these release contacts. When both relays are operated together, as will appear in the statement of the release, then a circuit is closed to the release magnet S^{13} and also to contacts of relay S^{14} , the test relay. When the latter operates it closes the circuit of release magnet S^{13} over conductor 96, conductor 66, and conductor 70 to ground. Inasmuch as terminals w^6 of switch W are disconnected from conductor 66, switch W is not affected by this release. The release of the first selector would accompany or follow momentarily the release of the second selector, a special release circuit being closed over conductor 1,001 by solenoid D' when the calling subscriber hangs up his receiver. Magnet S^{13} restores switch W' , and relay S^8 pulls up and closes circuit B, 1000, S^7 , ground to B, for the magnet S^7 which restores switch W . It is thus impossible for any subscriber to be tied up and lose control of his line, although if he should by mischance get into such a condition in my present system, he can get the operator's attention by continually flashing his lamp s^0 . This is one of the most striking features of the entire scheme, that the subscriber, while doing his own work, and free from listening in and interference on the part of the operator, can always get a human being to talk to and to get help from, when he so desires. It is not to be understood from this that the subscriber's operator listens to his complaints etc. The operator merely connects the subscriber's line with a cord circuit leading to a manual operator who has time and facilities for conversation. An ordinary plug and

jack connection may be used for this purpose.

The subscriber has now sent the digits to select two thousand two hundred, and wishes 5 to select twenty three. He gives a third series of two taps on the key, producing two breaks again. The same results as before follow as regards the solenoids D and D', and two impulses come over the wires 13— 10 67—97 through the branch wire 100 through relay S¹⁶ and by wire 101 to ground. Relay S¹⁶ pulls up twice, and each time closes the following circuit for the vertical stepper magnet S²⁰: B, 1000, 123, S²¹, 121, 146, 120, 15 springs of relay S²⁴, 119, 110, and ground. This steps up the spindle with its wipers, w⁵ and w⁶ to the second row. The subscriber having paused with the key K closed, the solenoids act to send a single pulse over the 20 rotary side of line as follows: B, 1000, 21, s², 22, s, 23, 28, 29, d⁴, d⁸, 34, 14, 68, 98, 102, S¹⁷, 101 and ground to B. Rotary relay S¹⁷ pulls up on this impulse closing the side switch control or private magnet circuit as 25 follows: B, 1000, S²⁴, 111, 110, ground to B. Magnet S²⁴ pulls up and falls back letting the side switch arms 146, 147, 148, and 149 go ahead a step, the first 146 disconnecting the vertical magnet S²⁰ and connecting the 30 rotary magnet through wire 122 and contact 151; the second and third passing onto blank contacts 154 and 157; and the fourth connecting the test wire 175 from the test wiper w⁵ to the wire 231 leading through contacts 35 of relay S²⁴ which are normally open as shown, to wire 230 and through release magnet S²³ to battery B. The subscriber now sends his last group of three breaks by tapping his key K. The circuit of the arm 146 40 having shifted from the vertical magnet S²⁰ to the rotary magnet S²¹, the latter responds by stepping the spindle around until the wipers w⁵ and w⁶ rest on the third pair of contacts in the row. This is the pair desired. 45 Now, as the subscriber pauses for the last time, the solenoids send their accustomed pulse of current again over the rotary side of line, 14—68—98, and the private magnet S²⁴ is again energized and deenergized thereby to let go the side switch. As soon as it is 50 energized, however, and before it can be deenergized, the line is tested. That is, the closing of the contacts of the magnet S²⁴ completes the following circuit: from wiper w⁵ by test wire 175, 149, 160, 231, contacts, 231, 230, S²³, 1000, and battery B to ground. The wiper w⁵ is looking for a ground. Now 55 it will be observed that if another line or switch is connected with the line wanted there will be a ground on the tip side of the line. That is to say, if another switch is already on the line then the ground will be by the path from the wiper contact w⁷ to the wiper on it, its wire to 155, 147, 130 and 60 129 to 124, relay S¹⁶ and ground. If an an-

swering plug has been inserted there will also be a ground on this tip side of the line from wire 9 (see Fig. 3), through the jack, plug tip and wire 11 to branch 17 and through the relay S to ground. So in either 70 event the relay or magnet S²³, which is testing, gets current before the relay S²⁴ can let go, and the switch is released without calling the line wanted or disturbing it. On the other hand if the line is not busy, that 75 is if there is neither plug nor switch in connection with it, then the test is clear, and the relay S²⁴ can let go, passing the side switch to the third position with all its arms. The arm 146 connects the wire 120 from the vertical relay to the ringing relay wire 127; the arm 147 connects the trunk wire 129—130 to the tip contact wiper w⁵; the arm 148 similarly connects the sleeve trunk wire 131—132 to the sleeve wiper w⁶; and the 80 arm 149 connects the test wire 175 to a blank 161, so as not to unbalance the talking circuit.

The calling line is now through to the line wanted, but ringing must take place. This 90 is accomplished by sending any number of impulses indeterminately with the key K. Each impulse, or break, produces an attraction of the armature of the vertical relay S¹⁶, which closes the ringing relay circuit as follows: B, 1000, 123, D², 127, 132, 146, 120, 119, 110, and ground. I preferably 95 make the relay D² a solenoid, as will be presently described, and so the numbers of short breaks cause the core—or armature—to be 100 attracted to break the talking circuit at d¹⁵—d¹⁶ and d²⁰—d²², connecting the springs d¹⁵ and d²⁰ to d¹⁴ and d¹⁰ respectively, which are connected to the generator G. In this 105 way the generator is connected to the wipers and ringing current sent to the wanted line. As the solenoid or relay lets go, the springs will again assume the positions shown, and complete the talking circuit. The called subscriber then answers and conversation 110 proceeds as usual. It is true that the talking circuit shown is through two pairs of condensers, but in another portion of the description a means for cutting these out during connection will be given. 115

When the subscribers have finished conversing, the receivers are returned to the hooks, and that of subscriber A produces the following results: The metallic circuit is 120 broken and remains broken, hence the relay S lets its armature stay back. This permits the core of solenoid D' to drop all the way for the first time since the call was first made, and in so doing to open springs d⁷ and d⁵ and close the springs d⁵, d⁸, and d¹¹, whereby current from wire 22 and 220 is carried to both trunk wires 13 and 14 through wires 34 and 36. This current passes over the trunk wires through the first and second selectors and to the connector W², where it goes 125 130

through the branches 100 and 102 and the magnets S^{16} and S^{17} to ground. Both these magnets are energized at once and their joint action closes the circuit of the release 5 as follows: B, 1000, S^{23} , 230, 112, 108, 99, w^6 , w^3 , S^{14} , s^{48} , 94 and ground. Magnet S^{23} closes and releases the connector switch mechanism by raising the detent pawls which hold the 10 spindle, allowing a retractile spring on the said spindle to turn it to zero position, when its own weight pulls it down to its normal level. At the same time relay S^{14} closes the circuit of its release magnet as follows: B, 1000, 75, S^{12} , 96, 66, 70 and ground to B. 15 This releases the switch W' and the release relay S^8 of switch W is energized, switch W being thereupon released as aforesaid. The retraction of the armature of relay S causes the lamps s^0 to glow continuously, and the 20 operator perceiving this signal pulls the plug P and thereupon the cut-off relay N and the control relay S^2 in the cord both let go their armatures, and the battery is reversed on the line again, while it is removed entirely from all the cord apparatus. The 25 solenoid D is thus finally let down, and all is ready for another call.

Two points remain for me to mention in respect to this arrangement. One is the 30 bridged battery for the called subscriber, which feeds current to his line from the main battery B through two impedance coils S^{18} and S^{19} . The other is the proper arrangement of the trunk and feed wires with respect to the cord circuit wires 11-12. With 35 a break on the side toward the line and battery coming on the other side of the condenser it is not always quite easy to get clear transmission, but if the connections are all reversed, that is if all the battery is supplied for the vertical and rotary relays from the other ends, and the solenoid put on grounds where I have shown them putting on battery, this trouble is entirely avoided. Also, if the 40 tip and sleeve contacts of the plug P are connected respectively to the wires 14 and 13, instead of as shown to the wires 13 and 14, or in other words the tip goes through its condenser to the rotary side of the 1st selector trunk instead of to the vertical side as shown, the result is quite satisfactory. The 45 interchange of grounds for battery connections, and battery connections for grounds, is of course not a matter of invention, as long as the circuits are unchanged thereby, nor is the connection of one side or the other of the plug circuit to one or the other of the selector trunk. I mention the 50 matter to make the practising of the invention perfectly easy and simple. The changes specified and many others are within the scope and purview of the invention.

Referring again to Figs. 3 and 4 I will now describe the operation of that part of 55 my system relating to selective party line

ringing. The operation of the first and second selectors and connector switch is identical with that described in Figs. 5 and 6 and need not be described a second time. In Figs. 3 and 4 I have for illustration shown a 70 subscriber calling a party on his own line. I have shown it in this manner so as to describe the method of calling back on the same line without its testing busy. Taking it for granted that the calling subscriber has sent the last set of vertical impulses through the connector switch in the manner already described in connection with Figs. 5 and 6, the wipers of the connector switch rest on the contacts leading to the desired line, in this 75 case his own line. After the last set of vertical impulses have been sent in there follows a long make at the subscribers station as usual. The relay S , Fig. 3, being energized at this time opens the circuit of the solenoid 80 D , allowing the core d to drop, momentarily closing the contact springs d^4 , d^6 and d^8 . An impulse is sent over the rotary side of the trunk as usual energizing the rotary relay S^{17} in the connector switch, Fig. 4, which connects the test relay S^{23} to the test wiper 149 of the side switch and from there to the tip side of the desired line. Ordinarily the 85 relay S^{23} would become energized on account of there being an answering plug in the jack. 90 thereby placing a ground on the tip side of the line. In this case, however, where the calling subscriber is calling back on his own line the test relay S^{23} is shunted in the following manner; at the same time the momentary impulse is sent in over the rotary side of the trunk a similar impulse is sent in over the tip side of the line by the following 95 path: Battery B, 21, s^2 , 22, s , 23, 28, 29, 32, d^4 , d^6 , 27, 11, 9, w^7 , w^5 . This impulse being 100 of the same polarity as that of the relay S^{23} neutralizes it, preventing it from becoming energized, thereby enabling a calling subscriber to call back on his own line. After 105 this rotary impulse has been sent in and the line not testing busy the calling subscriber is connected to contacts in the connector switch leading to his own line. The operation in calling a party on some other line would be 110 identical only the impulse sent in over the tip side of the calling line could not affect the test in the called line. Suppose he desires to 115 be connected with subscriber A' whose ringing number is 3, he manipulates the key K three times sending in that number of impulses operating the relay S^{16} in the connector switch, Fig. 4, which in turn closes the circuit of the solenoid D^2 by the following 120 path: Ground, 110, 109, 119, 115, 116, 120, 146, 152, 127, 126, D^2 , 125, 162, to battery. The solenoid D^2 pulls up at the first 125 impulse and simply vibrates as the other impulses come in. In pulling up it opens the contacts d^{15} , d^{16} , d^{20} and d^{23} , disconnecting the calling end of the trunk from the called 130

end to prevent generator current from flowing over the trunk to the calling subscriber. The contacts d^{21} , d^{22} are closed completing the circuit of the release magnet D^4 whose 5 armature now engages the ratchet wheel controlling the arms 144, 145. The operation of the relay S^{16} also closes the circuit of the stepping magnet D^3 by the following path: Ground, 110, 109, 119, 115, 116, 120, 146, 127, 10 128, D^3 , 133, to battery B. This stepping magnet responds to every impulse sent in over the vertical side of the line, and as three impulses were sent in it attracts its armature d^{30} carrying a pawl which engages 15 the ratchet wheel, moving the arms 144 and 145 three steps, thereby connecting current terminals from the generator G' to the contact springs d^{12} and d^{17} of the solenoid D^2 . These contact springs normally engage the 20 springs d^{13} and d^{18} , but while the solenoid is energized these contacts are broken preventing generator current from being connected to the called line until that of the proper frequency is actually selected. After the 25 three impulses have come in and the right kind of ringing current has been selected the solenoid D^2 becomes deenergized and the core d^o slowly drops. At the first movement the contacts d^{12} , d^{13} , and d^{17} , d^{18} are closed and 30 generator current is supplied to the called line by the following path: Over No. 3 side of the line from generator G' , 139, 145, 135^a, d^{12} , d^{13} , d^{14} , d^{15} , 130, 147, 155, w^6 , w^7 , 9, n , 1, 35 3, to station A'; over No. 6 side of the line from generator G' , 137, 144, 135, d^{17} , d^{18} , d^{19} , d^{20} , 148, 158, w^6 , w^8 , 10, n , 2, 6, to station A', thus ringing the bell Q' of the desired station. Generator current is supplied to the called line until the core d^o of the solenoid D^2 comes to a stop, when the contacts 40 d^{19} , d^{20} , and d^{14} , d^{15} are opened and the contacts d^{20} , d^{23} , and d^{15} , d^{16} are connected thus cutting off the generator current and connecting the calling end of the trunk to the 45 called end completing the talking circuit. At the same time the circuit of the release magnet D^4 is opened by breaking the contacts d^{21} and d^{22} , whereupon this magnet becoming deenergized allows its armature to 50 fall back, and releases the arms 144, 145 which, under the tension of a coiled spring, return to their normal or starting position. From the foregoing description of operation it will be observed that the calling subscriber's talking set is left bridged across its 55 line while ringing current is supplied to the called line. In party line service where the calling subscriber rings back on his own line this talking set is liable to shunt sufficient 60 current to prevent the bell of the desired party from ringing, since it is of low resistance in comparison with the ringers. In order to provide for this contingency I add an attachment to the polarized signal Q^o 65 which upon vibrating in response to the

generator current rapidly opens and closes its own circuit, which passes through the talking set, thereby introducing a high resistance in the bridge. In Fig. 8 I have shown this polarized signaling device Q^o 70 with its armature q^o , normally engaging one end of the L shaped lever q^{30} , the other end of which carries an adjustable weight q^{20} . The resistance coil X^{10} is normally shunted through the windings of the signal Q^{10} . 75 Ringing current flowing over the metallic circuit causes the armature q to vibrate. In vibrating it throws over the lever q^{30} which when adjusted by means of the ball q^{20} is nearly balanced. This lever is thrown forward violently by the armature and returns to its normal position rather slowly and during this interval the coils of the signal Q^{10} are disconnected and the talking circuit is completed through its resistance coil X^{10} . 80 This resistance coil is added as a means for keeping the relay S of the cord circuit energized while ringing, but it should be noted that the ringing generator current itself flowing out on the line will also flow back 85 through the supervisory relay S to ground and so keep it energized. In place of the shunt resistance I may use any variable resistance such as a carbon button and point which can be acted upon directly by the 90 armature q^o . It will also be noticed that for testing purposes I have used the tip side of the line, the test relay being connected to the free side of the battery. Instead of doing this I can use the sleeve side of the line for 95 testing purposes by having the test relay connected directly to the grounded side of the battery, as the cut-off line relay in this system is also connected to the grounded side of the battery and would therefore not interfere with testing. 100

At the end of the conversation the calling subscriber upon hanging up his receiver releases the various switches in the same manner as already described in connection with 110 Figs. 5 and 6 and the operator getting the disconnect signal withdraws the plug in the regular manner.

Referring now to Fig. 7 I have shown a modification of the connector switch illustrated in Fig. 6; which enables me to short circuit the condensers C^3 and C^4 and also disconnect the bridged release relays S^{16} and S^{17} , thus giving me a clear talking circuit back to the condensers in the cord circuit Fig. 3. The changes I make do not change or interfere with the operation of the switch. In place of the retardation coil S^{10} shown in Fig. 6, I substitute the relay S^{20} . The terminals of the relays S^{16} and S^{17} 115 instead of being connected directly to the trunk wires 97 and 98 respectively are connected indirectly through the contacts 201, 202 and 203 of the relay S^{20} . I have also added a locking relay S^{50} , one terminal 120

125 130

of which is connected to one of a pair of normally open contacts 210 and 209 which are controlled by the spindle w^4 . The other terminal of this relay is connected to a 5 normally open contact 208 of the relay S^{29} and the two contacts 230' and 231' respectively are connected to the contacts 206 and 207 of the same relay. The operation of this switch up to the point of calling and ringing the desired party is the same as already described and need not be described again. The difference in operation arises after the called party answers. In removing his telephone he closes the line circuit and energizes 15 the relay S^{29} . This relay thereupon attracting its armature opens the contacts 201, 202 and 205, 203, disconnecting the relays S^{16} and S^{17} and closes the contacts 200, 202, and 203, 204, short circuiting the condensers C^3 20 and C^4 . It also closes the circuit of the relay S^{50} by the following path: Battery B, 1000, 123, 218, 208, 214, S^{50} , 216, 210, to the contact 209 to ground. The contacts 209 and 210 were closed when the spindle w^4 made 25 its first step. The relay S^{50} attracting its armature closes the contacts 220, 230', 231', 232 to battery, thereby placing battery on the contacts 206 and 207 of the relay S^{29} which are now open. It will now be noticed 30 that the called party has control of the releasing of the switches, as the relays S^{16} and S^{17} which were controlled by the calling subscriber are now disconnected. The release is now effected in the following manner: 35 The called subscriber in hanging up his telephone deenergizes the relay S^{29} whose armatures upon falling back again connect the relays S^{16} and S^{17} to the trunk wires 97 and 98 respectively and remove the short circuit from the condensers. The contacts 208 and 218 which first close the circuit of the relay S^{50} are now broken but it still remains energized and locked by the following path: 40 Ground, 209, 210, 216, 232, 220, 217, 123, to battery. This relay remaining locked furnishes battery to the two relays S^{16} and S^{17} respectively through the contacts 207, 202, 201 and 206, 203, 205. These relays becoming energized simultaneously, effect the release of the connector and selector switches 45 by closing the following release circuit: B, 1,000, S^{23} , 230, 112, 108, 99, w^6 , w^3 , 80, S^{14} , s^{48} , 94, and ground to battery. The release magnet S^{23} immediately restores the connector 50 switch w^2 while the relay S^{14} closes the circuit of the release magnet S^{13} of the second selector by way of conductor 96, contacts of relay S^{14} , 66, 70, 69 and ground. The release of the first selector is however as 55 shown in Fig. 5 under the control of the calling subscriber. Not until the calling subscriber hangs up is his switch released. At that time solenoid D' is deenergized and by its lowermost contact d^9 puts battery onto 60 conductor 1,001 thereby energizing relay S^8

by way of side switch contacts s^{14} , 48, and conductor 59 to ground. The spindle w^4 when it has returned to its normal position opens the contacts 209 and 210 and releases the relay S^{50} whose armature when falling back removes battery from the contacts 206 and 207 deenergizing the relays S^{16} and S^{17} . In case the called subscriber did not answer the relay S^{29} would not be operated and the relay S^{50} would not be affected, and the calling subscriber in hanging up would 70 operate the relays S^{16} and S^{17} restoring the switches in the usual manner. 75

It should be noted that the arrangement of relays S^{29} , S^{16} and S^{17} , shown in Fig. 7 80 may well be employed without the locking relay S^{50} or the release circuits connected therewith. The function of relay S^{29} would then be merely to cut off relays S^{16} and S^{17} and shunt the condensers during conversation. It should also be observed that I have shown a special release wire 1001 in Fig. 5, connected at one end to the wire 61 of the release magnet S^8 , and at the other end to a back contact engaged by the battery wire 85 contact d^9 of the relay D' when down. By this means the calling subscriber has control of the switch W at all times and can restore it to make a recall. I consider this means of double release control to be original with me. 90 In the ringing circuit herein it should be noted that a battery such as B will be connected through an impedance coil to the sleeve side of the ringing circuit during 95 ringing in the ordinary way to hold up the cut off relay N. The ringing circuits shown in Fig. 4 can be replaced as to the selector switch arms 144—145 by any of the standard forms of circuits, with ground taps on opposite sides of line or the like. 100

I wish to make it plain that the apparatus and circuits herein described are fully applicable without any change requiring invention to full automatic. A subscriber's line circuit need only be connected permanently to the wires 11—12, and the control of test conditions given the relay S. The ringing scheme is contemplated for any type of system, as well as the reverting busy test. I do not wish to limit myself therefore to 110 the particular circuits described. 115

It will be noted that while I have shown means in Fig. 7 for short circuiting the condensers C^3 and C^4 in the connector circuit, and for cutting off the vertical and rotary 120 relays during conversation, this showing is omitted from Fig. 4, in order to simplify the drawing. It is to be understood that the short circuiting and cut-off relay may be substituted for the relay S^{19} in any circuit of 125 this kind where it is desired to have a clean path for talking currents.

I do not herein claim broadly automatic switches controlled by relays having different time constants or through impulses of 130

varying electrical characteristics transmitted over the subscriber's metallic line circuit (including the two sides of the line in series or other circuit normally free from ground connections) inasmuch as the same is claimed in my application Serial No. 291,097, filed December 9, 1905.

What I claim is:

1. In a telephone exchange system, a subscriber's line circuit, means at the subscriber's station to make and break the circuit, a source of current supply therefor, a central office equipment comprising a plurality of automatic switches through which 5 connections may be obtained with other subscriber's lines, said switches having distinctive actuating and control circuits, and means common to all the switches of a given connection directly operated by the subscriber in merely making and breaking the metallic line circuit, without grounding to distribute proper current impulses between the several switch control circuits of said 15 connection and to operate one or more of said switches, substantially as described.

2. In a telephone exchange system, a subscriber's metallic circuit and means controlled at the sub-station to make and break the circuit, a central office equipment comprising automatic switches requiring impulses over more than one circuit for their 20 operation and having distinctive actuating and control circuits, a source of current supply, and a pair of relays connected to the subscriber's line, common to all the switches of a given connection and arranged so that one will respond to line closures and the other to line breaks together with connections to the automatic switch control 25 circuits of said connection controlled by said relays, substantially as described.

3. In a telephone exchange system, a subscriber's line and means at the subscriber's station to make and break the circuit, a central office equipment comprising a relay responsive to the subscriber's line control, and a series of automatic switches having a plurality of controlling circuits separately energized for their operation, and a pair of distributing relays each having a definite time constant, controlled by the subscriber's relay and jointly controlling the several automatic switch circuits, substantially as described.

4. In a telephone exchange system, poly-station lines, means for selectively signaling thereover comprising a ringing circuit, a slow controlling relay therefor, selective ringing means, and a quick-acting selecting device therefor, the relay responding to all impulses, to disconnect or disable the ringing circuit until the desired selection is made, substantially as described.

5. In a telephone exchange system, poly-station lines, means for selectively signaling

thereover comprising a master relay controlling the application of signaling current to the line, and a selective apparatus actuated to connect the proper ringing circuit ready for application to the line, together 70 with means for simultaneously operating the master relay and the selective apparatus, substantially as described.

6. In an automatic telephone exchange system, a connector switch, a plurality of 75 selective ringing agencies, a ringing relay and a ringing selector associated with a connector switch, the former when actuated disabling the ringing circuit during selection, and the latter acting in response to circuit 80 changes to select and connect the desired ringing agency, substantially as described.

7. In a telephone exchange system, subscribers' lines including polystation lines, and automatic switching apparatus therefor 85 including switch contacts and subscribers' line terminals, a sending device and a switch controlling relay, together with selective ringing apparatus comprising the following instrumentalities: a slow relay and a select- 90 ing switch, both connected to be actuated through the controlling relay of the main switch, a ringing circuit, connections from the switch terminals to the ringing circuit controlled by the slow relay to keep ringing 95 current off the terminals and off the wanted line until the proper selection is made, and connections from the ringing circuit to one or more generator circuits controlled by the selecting switch, whereby any desired station 100 on a polystation line may be rung by merely continuing the ordinary manipulation of the sending and switch apparatus, substantially as described.

8. In a telephone exchange system, metallic circuit subscribers' lines having multiple terminals in automatic switch banks and connections in calling from a circuit to the switch circuits, a source of current and means at each subscriber's station to control the 110 flow thereof in his metallic circuit, a relay at the central office having back and front contacts, and responding to changes in the metallic circuit, two solenoids arranged so that they will pull up their cores quickly but 115 permit them to retract slowly, said solenoids connected respectively to the front and back relay contacts, a pair of condensers dividing the line metallic circuit from the automatic switch circuits but maintaining a continuous 120 path for conversation, and circuit connections from the respective switch circuits controlled by said solenoids, substantially as described.

9. In a telephone exchange system, an automatic connector switch circuit and apparatus comprising the following instrumentalities: connective terminals and a controlling side switch with working magnets connected in sequence thereby, metallic circuit 125 130

wires having answering and calling ends conductively separated but inductively united, a controlling relay connected to respond to current over the answering end, connections from said controlling relay to the working magnets, a bridged relay on the calling end of the circuits adapted to respond to the current flow therein when the called subscriber answers, and means controlled by said relay to cut off the controlling relays and short-circuit the condensers, so as to leave a clear metallic circuit for conversation, substantially as described.

10. In a telephone exchange system, an automatic connector switch circuit and apparatus comprising the following instrumentalities: connective terminals and a controlling side switch with working magnets connected in sequence thereby, metallic circuit wires having answering and calling ends conductively separated but inductively united, a controlling relay connected to respond to current over the answering end, connections from said controlling relay to the working magnets, a bridged relay on the calling end of the circuits adapted to respond to the current flow therein when the called subscriber answers, and means controlled by said relay in operating to place the subsequent control of the switch and its release in the hands of the called subscriber, substantially as described.

11. In a telephone exchange system, an automatic connector switch circuit and apparatus comprising the following instrumentalities: connective terminals and a controlling side switch with working magnets connected in sequence thereby, metallic circuit wires having answering and calling ends conductively separated but inductively united, a controlling relay connected to respond to current over the answering end, connections from said controlling relay to the working magnets, a bridged relay on the calling end of the circuits adapted to respond to the current flow therein when the called subscriber answers, and means controlled by said relay to cut off the controlling relays and short-circuit the condensers, so as to leave a clear metallic circuit for conversation, together with means operated upon actuation of said relay so as to place the control and release magnets of the switch under the control of the called subscriber's relay, substantially as described.

12. In a telephone exchange system, a subscriber's metallic line circuit 1-2 having multiple connection terminals, a metallic extension circuit 11-12, a battery B and a bridge relay S responding to makes and breaks in the subscriber's metallic circuit, automatic switches W, W' and W² with vertical and rotary and control circuits, and sluggish relays D, D' controlled by the relay S and controlling the circuits of the

switches to work the same, substantially as described.

13. In a telephone exchange system, a subscriber's metallic line circuit 1-2 having multiple connection terminals, a metallic extension circuit 11-12, working circuits 13-14, a battery B and a bridge relay S responding to makes and breaks in the subscriber's metallic circuit, automatic switches W, W' and W² with vertical and rotary and control circuits, and sluggish relays D, D' controlled by the relay S and controlling the distribution of impulses to the working circuits 13-14, said relay S repeating into the switch circuits in response to the subscriber's makes and breaks, substantially as described.

14. In a telephone exchange system, a poly-station subscriber's circuit 1-2, an extension circuit 11-12 therefor, a source of current B and a bridge relay S, automatic switch circuits 13-14 connected for conversation with the circuit 11-12 but conductively separated, automatic switch terminals w⁵, w⁶ and a test magnet S²³ connected therewith for testing and adapted to disable or release the switches upon finding a busy terminal, means associated with the wires 11-12 to change the condition of the line terminals in the switches W² when busy, a relay D and means controlled thereby operative in testing to expose the test magnet S²³ to the same potential on both sides through one of the extension wires 11-12 when the line tested is the line calling, substantially as described.

15. In a telephone exchange system, a line connector switch and selective ringing means comprising the following instrumentalities: a plurality of generator circuits and common generator wires adapted to be connected therewith, a controlling relay S¹⁰ responding to line impulses from the calling line, a solenoid D² and selector switch magnets D³, D⁴ controlled by said relay, the solenoid D² acting to disconnect the generator wires from the switch terminals during selection, and the selector magnets connecting said wires to the proper generator circuit as determined by the relay S¹⁰, substantially as described.

16. In a telephone exchange system, an automatic connector switch circuit and apparatus comprising a release magnet, metallic circuit wires having answering and calling ends, a controlling relay connected to respond to current over the answering end, connections from said controlling relay to said magnet, a bridge relay on the calling end of the circuit adapted to respond to current flow therein when the called subscriber answers, and means controlled by said relay in operating to place the subsequent control of said magnet solely in the hands of the called subscriber.

17. In a telephone exchange system, sub-

scribers' stations and a central station and metallic circuits interconnecting them, automatic switching apparatus at the central station for interconnecting lines, a plurality of 5 controlling magnets for said switching apparatus, means at each subscriber's station for varying the flow of current over the two sides of his line in series to produce groups of impulses varying in number according to 10 a predetermined code, and translating devices at the central office affected by said code changes in the metallic circuit and acting to distribute current to the switch controlling magnets to actuate the switching 15 apparatus to make a connection corresponding to the code changes produced by the calling subscriber, substantially as described.

18. In a telephone exchange system, a central office and a subscriber's station, 20 means at the substation to call central, line identifying means at the central station responsive thereto, a common battery for supplying current for talking and signaling purposes at said central station, means at the 25 central station to effect connection with the individual calling line, and an answer back signal at the substation actuated thereby, whereby the subscriber is apprised of his connection with the central station and may 30 thereupon effect the connection he desires.

19. In a telephone exchange system automatic switching devices, metallic line circuits, means at subscribers' stations to control the switches by making and breaking metallic circuits, ringing devices at the central office associated with the switching devices, and means whereby said ringing devices may be controlled by the same subscribers' controlling devices and in the same manner as the switches. 35

20. In a telephone exchange system, a central office and a plurality of subscribers' lines, one or more of said lines serving a plurality of substations, central office automatic switches, ringing selective devices associated 40 with said switches, a sending device at each subscriber's station, and means at the central office whereby the actuation of said sending devices to transmit successive numbers or code signals will both control the switching 45 devices so as to select the line and the party on the line, and thereafter actuate the ringer at the selected substation.

In testimony whereof I affix my signature in presence of two witnesses.

EDWARD E. CLEMENT.
